UNITED STATES PATENT OFFICE.

DON L. SMITH, OF SOUTH BEND, WASHINGTON.

SOAP BOX OR HOLDER.

Application filed September 11, 1924. Serial No. 737,137.

To all whom it may concern:

Be it known that I, DON L. SMITH, a citizen of the United States, residing at South Bend, in the county of Pacific and 5 State of Washington, have invented a new and useful Soap Box or Holder, of which the following is a specification.

This invention relates to soap holders for attachment to wash tubs, bath tubs and the 10 like.

The object of the invention is to provide a holder of this character which is simple in construction and cheap to manufacture and may be readily applied and removed 15 when desired.

Another object is to provide a soap holder having the container pivotally mounted to facilitate draining of the holder when the soap is removed.

20 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30 In the accompanying drawings:—

Figure 1 represents a perspective view of a soap holder constructed in accordance with this invention;

35 Fig. 2 is a plan view with the pivoted soap supporting member shown in elevated open position; and

40 Fig. 3 is a transverse section thereof showing the soap holder proper closed in full lines and open in dotted lines.

The holder constituting this invention comprises a box or shell 1 substantially rectangular in form as shown or of any other desired configuration composed of suitable 45 sheet metal having the upper edges thereof rolled to form beads 2 in which is mounted a reinforcing wire 3 the ends of which extend beyond the rear wall 4 of the casing and are downturned forming gripping arms 50 5 preferably inclined slightly outward toward their free ends and which are designed to fit over the upper edge of the wash or

bath tub in connection with which the device is to be used.

A cooperating spacing lug or stop 6 is 55 mounted on the rear wall 4 of the box and is designed to cooperate with the arms 5 in holding the box in proper position on the tub, said lug 6 being adapted to engage the inner face of the tub while the arm 5 engages the outer face thereof.

A rod 7 connects the inner ends of the arms 5 adjacent the upper edge of the rear wall 4 as is shown clearly in Figs. 1 and 3 and forms a pintle for the pivoted soap 65 containing member 10 which has knuckles 11 formed along its rear edge through which said pintle extends.

This soap holding member 10 is preferably made U-shaped in cross section and 70 spans the space between the front and rear of the box 1 the free front edge thereof being rolled as shown at 12 to snap down over the wire 3 at the front of the box which supports said holder 10 in operative position. This holder 10 as shown is provided with a plurality of openings here shown in the forms of slots 13 extending transversely of the holder and which are designed to permit water to drain therethrough into the 80 box 1 so that the soap will be protected against melting. This holder 10 is spaced a suitable distance from the bottom of the box 1 so that a considerable amount of water may collect in said box without coming in 85 contact with the soap.

In the use of this invention the arms 5 are hooked over the upper edge of a wash tub or bath tub with the stop 6 abutting against the inner face thereof and will thus 90 securely clamp the device on said edge, the soap being placed in the container 10 and held ready for convenient use.

When the device is not desired for use on a bath or wash tub it may be removed and 95 mounted in any other support or it may be set on a shelf or table.

I claim:—

A soap holder comprising a substantially rectangular water tight container having its 100 opposed ends rolled at their upper edges to form beads, a heavy wire inserted in said beads and extending around the front and rear edges of said container, arms depend-

ing from said wire at the rear thereof and cooperating with the rear wall of the container to form clamps for supporting the container on a support, and a soap holder

5 U-shaped in cross section and hingedly connected along one side edge with the wire in the rear of the container and having a hook-shaped lip at its front end to engage the

wire at the front end of the container, said soap holder having transversely arranged 10 slots to permit water to pass therethrough.

In testimony that I claim the foregoing as my own, I have hereto affixed my signature.

DON L. SMITH.
